(57) **CLAIM**

The ornamental design for a branch pipe, as shown and described.

DESCRIPTION

FIG. 1 is a front view of a branch pipe showing our new design, with the rear view, the left view, and the right view being identical;

FIG. 2 is a top view thereof;

FIG. 3 is a bottom view thereof;

FIG. 4 is a further front view thereof showing line 5-5; and, FIG. 5 is a cross-sectional view taken from area 5-5 of FIG. 4 showing the branch pipe in use.

The broken lines shown in the drawings illustrate environmental matter only that form no part of the claimed design.

1 Claim, 5 Drawing Sheets
